US0D1012611S

(12) **United States Design Patent** (10) **Patent No.:** **US D1,012,611 S**
(45) **Date of Patent:** **** Jan. 30, 2024**

(54) **MULTIFUNCTIONAL GRILL**

(71) Applicant: **Xiamen Xianbangda Trading Co., Ltd.**, Fujian (CN)

(72) Inventor: **Lei Tang**, Fujian (CN)

(73) Assignee: **Xiamen Xianbangda Trading Co., Ltd.**, Fujian (CN)

(**) Term: **15 Years**

(21) Appl. No.: **29/913,231**

(22) Filed: **Sep. 28, 2023**

(30) **Foreign Application Priority Data**

Sep. 15, 2023 (CN) 202330602008.5

(51) **LOC (14) Cl.** **07-99**

(52) **U.S. Cl.**
